Primary Examiner — Lauren R Calve(74) *Attorney, Agent, or Firm* — Thompson Hine LLP(57) **CLAIM**

The ornamental design for a rotary knob, as shown and described.

DESCRIPTION

FIG. 1 is a front view of the rotary knob according to my design;

FIG. 2 is a left view of the rotary knob of FIG. 1;

FIG. 3 is a right view of the rotary knob of FIG. 1;

FIG. 4 is a top view of the rotary knob of FIG. 1; and,

FIG. 5 is a bottom view of the rotary knob of FIG. 1.

The broken lines in the Figures depict portions of the rotary knob that form no part of the claimed design.

1 Claim, 5 Drawing Sheets(56)
